(57) **CLAIM**

The ornamental design for a square post surgical clamp, as shown and described.

DESCRIPTION

FIG. 1 is a perspective view of a square post surgical table clamp, showing my new design;

FIG. 2 is a front elevational view of the invention; the rear elevational view being mirror image thereof;

FIG. 3 is a left-side elevational view of the invention;

FIG. 4 is a right-side elevational view of the invention;

FIG. 5 is a top plan view of the invention; and,

FIG. 6 is a bottom plan view of the invention.
